(57) **CLAIM**

The ornamental design for an organizational mat as shown and described.

DESCRIPTION

FIG. 1 is a front, top, left side isometric perspective view of an organizational mat in accordance with my design; FIG. 2 is a front, bottom, right side isometric perspective view of the organizational mat;

FIG. 3 is a top plan view of the organizational mat; FIG. 4 is a front elevation and left side elevation view of the organizational mat;

FIG. 5 is a rear elevation and right side elevation view of the organizational mat;

FIG. 6 is a bottom plan view of the organizational mat; and, FIG. 7 is a cross-section of the organizational mat shown in the direction of line 7-7 of FIG. 3.

The dot-dot-dash broken lines depict symbolic breaks in the organizational mat.
